UNITED STATES PATENT OFFICE

RUPERT HUNTLEY AND HAROLD E. WICKHAM, OF TORONTO, ONTARIO, CANADA

DESIGN FOR A COMBINED DISPLAY DEVICE AND CLOCK

Application filed August 27, 1931. Serial No. 40,936. Term of patent 3½ years.

To all whom it may concern:

Be it known that we, RUPERT HUNTLEY and HAROLD E. WICKHAM, both subjects of the King of Great Britain, residing at the city of Toronto, in the county of York, Province of Ontario, Canada, have invented a new, original, and ornamental Design for a Combined Display Device and Clock, of which the following is a specification, reference being had to the accompanying drawings, forming part thereof in which the cabinet portion is octago-

nal in cross section, in which the reverse side is substantially the same as the front side and in which Fig. 1 is a perspective view of our device; and Fig. 2 is a small diagrammatic plan view thereof.

We claim:

The ornamental design for a combined display device and clock substantially as shown and described.

RUPERT HUNTLEY.
HAROLD E. WICKHAM.
